DESIGN FOR A SIGNAL COVER GLASS

Charles Adler, Jr., Baltimore, Md.

Application March 9, 1934, Serial No. 50,993

Term of patent 14 years

To all whom it may concern:

Be it known that I, CHARLES ADLER, JR., a citizen of the United States, residing at the city of Baltimore, and State of Maryland, have invented a new, original, and ornamental Design for a Signal Cover Glass, of which the following is a specification, reference being had to the accompanying drawings, forming a part thereof.

Figure 1 is an elevation of the cover glass;

Figure 2 is an enlarged view in elevation of a portion of the cover glass shown in Figure 1;

Figure 3 is a section on the line 3—3 of Figure 1; Figure 4 is a section on the line 4—4 of Figure 1;

Figure 5 is a section on the line 5—5 of Figure 2; and

Figure 6 is a section on the line 6—6 of Figure 2.

I claim:—

The ornamental design for a signal cover glass as shown.

CHARLES ADLER, JR.
